(57) **CLAIM**

The ornamental design for extension bracket for display mount, as shown and described.

DESCRIPTION

FIG. 1 is a perspective view of the subject extension bracket for display mount;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the subject extension bracket for display mount shown assembled in the environment in which they are intended to be used.

The broken lines in the drawings depict environmental subject matter only and form no part of the claimed design.
